FIG. 3.

FIG. 4.

Inventor
N. C. L. Brown,
By his Attorney
Neil H. Preston

UNITED STATES PATENT OFFICE.

NED C. L. BROWN, OF SCOTTSVILLE, NEW YORK, ASSIGNOR TO GENERAL RAILWAY SIGNAL COMPANY, OF GATES, NEW YORK, A CORPORATION OF NEW YORK.

TRAIN CONTROL.

Application filed May 29, 1923. Serial No. 504,517.

To all whom it may concern:

Be it known that I, NED C. L. BROWN, a citizen of the United States of America, residing at Scottsville, in the county of Monroe and State of New York, have invented certain new and useful Improvements in Train Controls, of which the following is a specification.

This invention relates to train control systems, and more particularly to means for communicating control influences from the trackway to a moving vehicle.

In train control and cab signaling systems, it is necessary to communicate suitable control influences from the trackway to the moving trains. Such control influences are preferably transmitted through an air gap, rather than by physical contact between devices on the vehicle and devices along the trackway, because among other things devices making physical contact wear away rapidly, and are apt to interfere with other objects on the train or vehicle. In one particular type of system to which this invention more particularly relates, the control influences are transmitted inductively by employing magnetic devices along the trackway cooperating with devices on the vehicle, the track devices being of the character conveniently termed the inert type, that is, devices which do not require any energy from a transmission line or from a track battery to put them in the non-stopping or inactive condition. Such an inert element is desirable, because a source of energy along the trackway is not only expensive, but is not always reliable.

In the particular system above referred to, the track element comprises a magnetic core which is located along the trackway and is adapted to influence a car element by changing the reluctance of the magnetic circuit of said car element, such change in reluctance being utilized, by electro-magnetic induction or otherwise, to actuate a relay or other device so as to obtain the desired controlling influence. When the track elements are located between the track rails, they can not project much, if any, above the top of the rails, otherwise they may be struck by low parts of the rolling stock. Also, the lowest part of the car element has to be kept above the top of the rails, so as to clear the track rails at crossings, switches and the

like. These practical limitations make it necessary to work through a relatively large air gap of two or more inches, this air gap also varying somewhat as the wheels of the vehicle wear down. Variation in battery voltage, resistance of the coils or windings with temperature changes and other conditions, alter the strength of the influence communicated at different times by the same track devices. Under certain adverse circumstances, a false controlling influence may be received with the arrangement just described, because other magnetic bodies, such as crossing rails, impedance bonds, switch frogs and the like, will also tend to reduce the reluctance of the car element passing thereover and are apt to transmit an influence, thereby bringing the train to a stop unnecessarily.

With the above and other considerations in mind, one of the principal objects of the present invention is to use a plurality of car elements and track elements arranged in such a manner on the car and on the track that, while these elements will be juxtaposed and communicate the desired control influence, track rails or like magnetic bodies on the track will not produce the same effect and cause false operation of the train control apparatus.

Other objects and advantages of the invention will appear as the description progresses.

In describing the invention in detail, reference will be made to the accompanying drawings, in which:

Fig. 1 shows diagrammatically the trackway equipment embodying the present invention, the parts and circuits being shown more with a view of making it easy to understand the nature and mode of operation of the invention, than with the purpose of illustrating the exact construction preferably employed in practice;

Fig. 2 is a simplified and diagrammatic perspective view of one form of car-carried equipment;

Fig. 3 shows a modified form of car-carried equipment; and

Fig. 4 is a diagrammatic view for facilitating explanation of the invention.

The impulse transmitting means embodying the present invention comprises, in general, a pair of track elements T and U which

are located at the desired control points along the track, and which are suitably controlled in accordance with traffic conditions, and a pair of car elements L and M and associated parts which cooperate with said track elements so as to cause interruption of a circuit on the car, or in some other suitable way produce an action on the car under dangerous traffic conditions which may be utilized in any one of the well-known ways to regulate and control the movement of the car or train.

Various arrangements of trackway circuits for controlling the operating condition of the track elements T and U may be employed, and in the accompanying drawings there is shown only one typical arrangement. Referring to Fig. 1, the track rails are divided by insulated joints 1 into blocks in the usual way, one block I with the adjacent ends of two other blocks H and J being shown. Since the parts associated with the various blocks are the same, for convenience they will be given like reference characters with distinctive exponents. Each of the blocks is provided with a track battery 2, a track relay 3, a line relay 4, and suitable track equipment for the train control system.

While the system of train control embodying this invention may be used with or without the usual fixed trackway signals of a block signal system, in the particular arrangement illustrated, it is assumed that some suitable form of a block signal system will be employed in conjunction with the train control system. Such arrangement is considered preferable on the theory that a train control system should be an adjunct to the block signal system and afford a supplementary protection to train movements afforded thereby, rather than as a substitute.

In Fig. 1 the usual fixed semaphore signal S at the entrance to each block has been illustrated conventionally. These signals S may be of any well-known type; and the specific construction and detailed operation of such signals is familiar to those skilled in the art. No specific operating mechanism for the signals S has been illustrated, because suitable constructions are well-known in the art and are no part of the present invention, and further in order to omit unnecessary structure which would complicate the understanding of the present invention.

For the purposes of the present invention, it is sufficient to note that in practice the semaphore blade is biased by its own weight to the horizontal, zero degree or danger position, and is provided with a motor, gearing hold-clear device and automatic circuit controller, these parts being organized so as to cause the semaphore blade to be driven in opposition to its bias to an inclined, caution or 45 degree position and held there, when the 45 degree control circuit is energized, or

still further to a vertical, clear or 90 degree position, when the 90 degree control circuit is energized.

Each signal S is provided with two circuit controllers 5 and 6, respectively, which are illustrated in accordance with established convention and are in practice operatively connected to the semaphore operating mechanism. The circuit controller 5 is in circuit closing position only when its signal S is in the clear or 90 degree position, and acts to connect the coils of the track elements T and U in a closed circuit of preferably low resistance when the semaphore is in its clear position. The other circuit controller 6, as indicated by the arcuate segment, is closed in the caution and also in the clear position of the semaphore arm, and in all immediate positions, thus interrupting the circuit of the line relay 4 one block in the rear and putting that rear signal at caution when the signal in question is at danger.

Along the trackway are provided track elements T and U which comprise U-shaped cores 8 of soft iron, preferably laminated, these cores being provided with enlarged pole pieces 9. These track elements are preferably positioned so that the legs fall on the four corners of a square, as shown. Each leg of the cores 8 is provided with a coil 10; and these coils 10 are so wound and connected that the voltages induced therein, by a change in flux passing through the cores, will be cumulative or in the same direction. The effectiveness of these track elements T and U upon the car elements L and M may be controlled directly by a line or track relay, or both, but I have illustrated them as being controlled by the circuit controller 5 of the adjacent corresponding signal S, whereby the coils 10 of the track elements T and U will be open-circuited, or put in their influence transmitting condition, when the semaphore blade of that signal is in either the caution or stop position, or in fact in any other except its 90 degree position.

The influence communicating means of this invention may be employed to set into operation or otherwise control any suitable or desired form of cab signal or brake control device, depending upon the character of regulation of train movement it is desired to obtain. In the car-carried equipment illustrated in Fig. 2, the train control device K has been shown in the form of an electro-pneumatic valve which may be used to vent the train pipe directly, or which may be used to control other train control apparatus which depends for its actuation upon certain other conditions, such as the speed of the train, the brake pipe pressure, the position of the train in the block, and other factors entering into the desired reg-

ulation or control of the moving train. In the arrangement shown, this train control device K comprises a valve having stick features, that is, it is constructed so that, when it has once been opened, it remains open until the difference of pressure on opposite sides of the valve has been reduced to a certain amount, such, for instance, as shown in the application of W. K. Howe No. 10 387,527, filed November 12, 1919. This valve is normally held closed when the solenoid 11 is energized, and will open if this solenoid 11 is momentarily deenergized, such momentary deenergization leaving the valve open until reset, due to the stick features of the valve.

It should be understood that the construction and operation of the train control device K just described, is merely illustrative of the type of device which can be used for the purpose, for instance, of automatically routing the brake pipe to produce an automatic brake application; and it should be understood that this device will be appropriately constructed to limit the amount of brake pipe reduction, prevent the engineer from recharging and avoiding the brake application, and otherwise conform with approved air brake practice.

Although the train control device K may be constructed to be operated directly by influences received from the trackway, it is preferably controlled by a control relay R. This control relay R is designed in accordance with principles familiar to those skilled in the electrical art so as to be quick acting, and in other respects operate to the best advantage under the conditions hereinafter explained. Among other things, this relay is constructed or mounted in some suitable manner, forming no part of the present invention, so as to be protected from false operation by jar and vibration. This control relay R in turn is preferably controlled by two thermionic or vacuum bulb amplifiers 12 and 13 of the well-known commercial type, commonly known and conveniently designated as "audions". These audions have been diagrammatically illustrated, and have the usual filaments F and F¹, grids G and G¹ and plates H and H¹, respectively.

On the vehicle, represented diagrammatically by the car axles 14 and 15, are mounted two car elements L and M of general U-shape, each having two downwardly extending legs provided with enlarged pole pieces 16. These elements are in effect U-shaped cores, and are preferably made of soft iron laminations. The two elements L and M are mounted on a railway vehicle so that the pole pieces 16 come slightly above the top of the rails, and are so disposed that the four legs fit over, so to speak, the corresponding legs of the

track elements T and U. These car elements may be magnetically connected, either by a back yoke 17 as shown, or by mounting these elements directly on the truck, car frame or other support which is constructed of magnetic material. One leg (shown as the lefthand leg) of the forward car element L and the diagonally opposite leg (shown as the righthand leg) of the rearward car element M are provided with primary coils 18 and 19, respectively, which are connected in series in a manner, so that when said coils are energized, these legs will be magnetized with opposite polarities, that is, for example, the coil 18 will produce a north pole, while the coil 19 will produce a south pole. In other words, the magnetic flux in forward car element L produced by its energized primary coil 18 will be in one direction, while the flux in the following car element M will be in the other direction.

The primary coils 18 and 19 are connected in series with the train control device K across the batteries B and C, with the front contact of the control relay R in the circuit, which may be traced as follows: beginning at the positive side of the battery C, wire 39, primary coil 18 of the car element L, wire 40, primary coil 95 19 of the car element M, wire 41, winding 11 of the train control device K, wire 42, front contact 43 of control relay R, wire 44, back to the negative side of the battery B. Thus, when the control relay R is de- energized the train control device K will be operated, and further an interruption of the circuit through the primary coils 18 and 19, or the depreciation of the battery, will cause the train control device K to be operated, thereby effecting an automatic check upon the integrity of this circuit.

The other leg of the car element L is provided with a secondary winding 20; and the other leg of the car element M is similarly provided with a secondary winding 21. The secondary coil 20 is included in the grid circuit of the audion 12, this circuit being traced as follows:—starting at the positive side of the battery B, wire 32, secondary winding 20, wire 33 to the grid G of the audion 12, through the audion to its filament F, back to the negative side of the battery B. The secondary coil 21 is included in the grid circuit of the other audion 13, said circuit being traced as follows:—starting at the positive side of the battery B, wire 32, secondary winding 21, wire 34 to the grid G¹ of the audion 13, through the audion to its filament F¹, back to the negative side of the battery B.

Under normal conditions, that is, when a vehicle provided with the car-carried equipment illustrated in Fig. 2 is traveling between control points and is not being in-

fluenced by track devices, the parts and circuits will be in the condition shown in the drawing. The filaments F and F¹ of the audions 12 and 13 will be heated by the battery A, and the potential of the battery B will be impressed through the secondary winding 20 upon the grid G, and through the secondary winding 21 upon the grid G¹, thus reducing the resistance of the plate circuits, thereby causing a current to flow in the plate circuit of each audion 12 and 13 of sufficient magnitude to maintain the control relay R magnetized to keep its front contact 43 closed. These plate circuits may be traced as follows:—beginning at the positive side of the battery C, wire 35, winding of the control relay R, wire 36, wire 37 to the plate H of the audion 12, through the audion to its filament F through the battery B and to the negative side of the battery C; and another circuit beginning at the positive side of the battery C, wire 35, winding of the control relay R, wire 36, wire 38 to the plate H¹ of the audion 13, through the audion to its filament F¹, through the battery B and back to the negative side of the battery C.

Before taking up in detail the operation of the train control system, it is convenient to explain the operation and condition of the trackway circuits, signals, and track elements under different traffic conditions. For the sake of simplicity in illustrating the trackway circuits, the batteries or other sources of current for these circuits have not been shown, but wires terminating at P and N indicate a direct connection to a battery, either local or over a common wire, it being of course understood that the same or different batteries may be employed in the respective circuits in accordance with well-known practice. The control circuits for each signal, and the control circuit for the corresponding track elements are the same, and the description of one will suffice for all.

If the block J is occupied by a train, the track relay 3¹ is robbed of its energizing current due to the shunting action of the wheels and axles of this train; and consequently this track relay drops its armature and opens both the 45 degree or caution control circuit and the 90 degree or clear control circuit for the signal S¹, thereby causing the signal to assume the zero degree or danger position. The movement of the signal S¹ to the horizontal or stop position opens the circuit controlled by the circuit controller 6¹, thereby deenergizing the line relay 4 at the signal S next in the rear. The dropping of the line relay 4 interrupts the 90 degree or clear control circuit for the signal S, causing it to assume its 45 degree or caution position. Thus, with a train in the block J, signal S¹ is in the stop posi-

tion and the signal S is in the caution position.

The coils 10 of the track elements T and U of each block are included in a circuit which may be traced as follows:—commencing at the upper coil 10 of the track element T, wire 23, lower coil 10, wire 24, circuit controller 5 of signal S, wire 25, lower coil 10 of track element U, wire 26, upper coil 10 of track element U, and wire 27. With the corresponding signal in either the caution or stop position, the circuit controller 5 is open, thereby opening this circuit including the coils 10 of the corresponding track elements T and U. In other words, the track elements T and U are in the active stopping condition at each caution or stop signal. It will be obvious, however, that the control of these track elements may be modified so as to produce a stop control only at a stop signal, or only at a caution signal, the particular manner of control desired depending upon the type of train control apparatus on the train to be governed.

Referring now to the operation of train control system, the normal condition of the car equipment while traveling between control points under safe traffic conditions has been previously pointed out. Assume now that the car, equipped as shown in Fig. 2, with the various devices and circuits thereon in the normal condition as shown, is approaching the track elements T and U in their active stopping condition, that is, with their coils 10 in an open circuit. The track elements T and U in this active stopping condition constitute in effect what may be termed a dead magnetic loop or partial circuit; or, putting it another way, these track elements serve to act as a bridge of low reluctance for the cores of the car elements L and M as the car passes over said track elements. The effect of these track elements in their active stopping condition is to greatly reduce the reluctance of the partial magnetic circuit through the car elements L and M; and this change in reluctance causes first an increase in the magnetic flux or lines of force, produced by the primary coils 18 and 19, through the secondary coils 20 and 21, as the car elements approach the track elements. As the car elements come directly over the track elements, the reluctance is a minimum, the total flux a maximum, and the rate of change of flux zero. Thus, there is induced in the secondary coils 20 and 21 a single cycle of alternating current as the car elements approach, pass over, and recede from the track elements. The voltage induced in the secondary coils 20 and 21 will have a polarity or direction in the external circuit of these coils depending upon the magnetic polarity of the corresponding primary coils, the direction in which these secondary coils are wound on the cores, and the

manner in which these coils are connected into their respective circuits. For ordinary conditions, the connections are preferably made so that the voltage of the first wave or 5 half cycle is in a direction to oppose the battery B; but other arrangements and combinations of circuits can be used. In any event, during the passage of the car elements over the track elements in their active stopping condition, the voltage of the battery B is temporarily opposed by a voltage induced 10 in the secondary coils 20 and 21, thereby reducing the grid potential of the audions and in turn reducing the plate current. 15 It will be noted that the normal energizing current of the relay R is in effect made up of two parts, that flowing in the plate circuit of the audion 12, and that flowing in the plate circuit of the audion 13. Putting it another way, the energizing circuit 20 for the relay R may be said to have two multiple branches with an electro-responsive device in each branch, these electro-responsive devices being separately influenced by 25 voltage changes in the secondary coils 20 and 21. Now, when the car elements L and M pass over the track elements T and U, the voltage waves in the secondary coils 20 and 21 are in time phase, that is, rise and fall 30 simultaneously, since the spacing of the cores of the track elements corresponds with that of the cores of the car elements. Thus, the grid potentials of the two audions 12 and 13 are simultaneously affected, and likewise the reduction in the current flowing in 35 the two plate circuits through the relay R occurs simultaneously. The various battery voltages, windings, resistances and devices, are selected and proportioned so that 40 concurrent reduction in the current normally flowing in the plate circuits of the audions, reduced by the passage of the car elements over their respective track elements, brings about a decrease in the total 45 current through the relay R to a point below the dropaway or holdup value for said relay, so that the armature of the relay is retracted by its bias, thereby opening the 50 circuit through the train control device K and setting said device into operation.

The dropping of the armature of the relay R is only momentary, and the train control device K is of course constructed so as to continue in operation and impose the 55 desired control over the train in response to such momentary opening of its energizing circuit; but since this end may be obtained in various ways, by the provision of stick contacts and the like, such, for instance, as shown in the application of W. L. Howe heretofore referred to, and since the 60 particular structure of the train control device itself forms no part of the present invention, no attempt has been made to show 65 any specific structure for this purpose, or

the provisions that would be also required for restoring the train control device K, manually or automatically, to its initial condition after it has performed its desired function in controlling the train. It should 70 be noted that the car element L must pass over the track element U before it reaches the track element T. Such passage of the car element L over the track element U produces substantially the same effect on the 75 grid G of the audion 12 as when it passes over the track element T, that is, assuming that the track elements are in their active condition. Such influence upon the grid G causes an instantaneous decrease in current flow through the relay R. This drop in current does, however, not bring the current below the dropaway value, and therefore does not cause the relay R to drop. A similar effect is produced on the grid G 80 of the audion 13 when the car element M passes over the track element T after simultaneous registration of car elements L and M with track elements T and U respectively; that is, when the car elements L and M 85 recede from the track elements T and U after cooperation of these respective elements.

The foregoing operation occurs at each 90 pair of track elements T and U which have 95 their control circuits open. According to the particular arrangement of the trackway circuits shown in Fig. 1, such operation occurs at each caution signal and also at each stop signal; but it is evident that by appropriate arrangement of control circuits, this stopping influence may be communicated at stop signals only or at caution signals only, or in fact at any desired control point along the track where there are no signals. 100 Similarly, track elements without coils 10 may be located at any desired point along the track where it is desired to communicate a stopping influence for every train at all times, such as at the approach to a fixed 105 hazard. These, and other adaptations of the invention, will be evident to those skilled in the art and need not be specifically shown and described.

Assume now that the vehicle, equipped as 115 shown in Fig. 2 and with its parts in the normal condition illustrated, approaches a signal in the clear or proceed position. Under these conditions, the control circuit for the track elements T and U associated 120 with that signal is closed by the circuit controller 5, thereby placing the coils 10 of said track elements in a closed circuit of low resistance. In Fig. 1, this circuit connection is shown as putting the coils 125 10 of the two track elements T and U in series, but the same result may be obtained by including the coils of the respective track elements in separate closed circuits. In either case, the coils 10 of the track ele- 130

ments being in a closed circuit will have a tendency to oppose any change in flux through the cores of said track elements, since such change in flux would induce a 5 current in these coils and this current, in accordance with well-known laws, would be in a direction to create a magnetic field opposing the flux inducing that current. Consequently, as the car elements L and M 10 pass over the track elements T and U with their coils in a closed circuit of low resistance, the quick change in flux through the secondary coil 20 and 21 does not occur, due to the fact that the coils 10 of the track 15 elements oppose such rapid change of flux. Thus, the grid potentials of the audions 12 and 13, although simultaneously affected, are not reduced sufficiently to allow the armature of the relay R to drop.

20 One of the important characteristics of the present invention resides in the provisions made to avoid premature or false operation of the car equipment by magnetic bodies, such as track rails, ordinarily encountered along the track. It will be readily seen 25 that the stopping influence in the system of this invention is produced by the magnetic qualities of the track elements; and accordingly a stopping influence of the same character is to a certain degree produced by the track rails at crossings, switches, water pans, and other magnetic bodies along the track. Such track rails and other magnetic bodies 30 do not of course produce as strong an effect upon the car equipment as the track elements, because the track elements are made of a good quality of magnetic material, laminated to avoid iron losses, and have a cross section such as to make these track elements 35 much better magnetic conductors than ordinary track rails or the like. In addition to the superiority of the regular track elements in their effect upon the car equipment, according to this invention the particular arrangement of the track elements in connection 40 with the arrangement of the car elements enables the track elements to produce an effect far greater than can be produced by track rails or other magnetic bodies ordinarily encountered along a railroad track.

45 To make clear this important characteristic of the present invention, it will be explained how track rails extending transversely to the running rails having various angles fail to affect the relay R appreciably. Referring to Fig. 4, assume that the car elements L and M, traveling in the direction indicated by the arrow approach and pass over 50 the track rail of the right angle crossing, indicated by the line 50. This track rail will first complete the partial magnetic circuit for the car element L, and then for the car element M. If the car elements L and M are spaced apart a distance depending upon the 55 range or zone within which flux changes occur

in the secondary coils due to the passage of iron bodies, then it will be readily appreciated that the track rail 50 will produce its cycle of voltage in the secondary coil 20 before producing any voltage in the secondary 70 coil 21. In other words, the track rail 50 produces its effect upon the leading car element L fully before affecting the trailing car element M. Consequently, the grid potential of the audion 12 is changed and returns to normal before the grid potential of the audion 13 is affected, with the result that the relay R always has in it a current equal to the full current through the plate circuit of one audion, together with the reduced 75 current in the plate circuit of the other audion; and since, as previously explained, the currents in the plate circuits must be concurrently reduced to a predetermined low value in order to cause the relay R to drop, it can be seen that the track rail 50 does not produce such operation.

80 If the track rails are disposed at an angle to the running rails, their effect upon the car elements becomes less as the track rails become more and more nearly parallel with the running rails, since such track rails present little more than their width as a magnetic conducting path for flux through the cores 85 of the car elements. For example, referring to Fig. 4, a track rail disposed nearly parallel with the running rails and the direction of movement of the vehicle, as indicated by the line 51, adds very little iron to the partial magnetic circuit through the 90 cores of the two car elements L and M, so that there is produced very little change in flux in the secondary coils. It may be added that, on account of the relatively large air gap between the car elements and the track- 95 way bodies, whether the regular track elements or crossing rails, the inclusion of a small amount of iron in the magnetic circuit of the car elements produces a negligible effect, the greater part of the reluctance 100 of the magnetic circuit being due to air gap, so that a small amount of iron has proportionally less effect.

105 In any event, a track rail to a large extent, regardless of its angular relation to the running rails, fails to influence the secondary coils 20 and 21 simultaneously and to the same degree so as to produce the necessary reduction in the energizing current of the relay R to cause its armature to drop. Even 110 though there is a slight overlapping in the voltage waves induced in the secondary coils 20 and 21, their cumulative effect upon the energizing current of the relay R is bound to be less than if these waves are exactly in 115 time phase, as in the case of the regular track elements. For example, imagine a track rail disposed at about 45 degrees to the running rails, as indicated by the line 52 in Fig. 4, and visualizing the position of this 120

rail with respect to the cores of the car elements L and M as the car travels over said rail, it will be seen that the position of this rail with respect to the secondary coils 20 and 21 to cause voltage changes in these secondary coils to the best advantage, takes place successively in much the same way as in the case of the right angle rail 50. The same is true for a rail disposed at about 45 degrees in the other direction, as indicated by the line 53.

In addition to the protection against false operation by angularly disposed track rails obtained by the lack of simultaneous effect upon the secondary coils, the addition of the back yoke 17 serves to cause the effect upon one secondary coil to be neutralized to a certain degree by the effect upon the other secondary coil. To illustrate, imagine a track rail disposed as indicated by the line 52, and that the car elements have progressed to the point where this track rail lies about midway between the ends of the core of the leading car element L. This track rail, it will be observed, will also constitute a sort of magnetic bridge for the primary coil 18 of the car element L and the secondary coil 21 of the car element M, the iron path on the vehicle being completed by the back yoke 17. Thus, at the same time that there is a change of flux in the secondary coil 20, there is a similar change in flux in the secondary coil 21, this flux being produced by the primary coil 18 in both instances. As previously explained, the primary coils 18 and 19 are wound to give opposite magnetic polarities, and similarly the secondary coils 20 and 21 are oppositely wound and connected, with the net result that an increase or decrease of flux simultaneously in the two secondary coils 20 and 21, when that flux is derived from the same primary coil and has the same polarity, induces voltages in these secondary coils which are opposite, so that as the induced voltage in one secondary coil reduces, for instance, the grid potential of its corresponding audion, likewise decreasing the flow of energizing current for the relay R, the induced voltage in the other secondary coil increases the grid potential of its audion and correspondingly increases the flow of energizing current in the relay R. In short, as the rail 52, by its effect upon one secondary coil 10 tends to drop the relay R, the same rail at the same time by its effect upon the other secondary coil tends to hold up the relay R. The same theory of operation holds true as the rail 52 in question comes to the point where it bridges the primary coil 19 of the car element M, its secondary coil 21, and the secondary coil 20 of the car element L.

In the case of a rail disposed at an angle

indicated by the line 53, it will be seen that this rail establishes magnetic communication, so to speak, between the two primary coils 18 and 19 and the secondary coil 20 concurrently; and since the magnetic-motive-forces of the primary coils 18 and 19 are opposing, there is little, if any, change of flux in the secondary coil 20. The same is true as the rail 53 reaches the point where it connects magnetically the secondary coil 21 with the two primary coils 18 and 19. In addition to this, it is believed that the opposite magnetic polarities of the primary coils 18 and 19 result in the tendency for these primary coils to send flux down and through the track rail 53, rather than through either of the secondary coils 20 and 21.

In the foregoing explanation of the manner in which the car apparatus of this invention is effectively influenced by the regular track elements and is not materially, at least sufficiently to cause false operation, influenced by track rails or other magnetic bodies disposed at various angles to the running rails, attention has been limited to the individual features of the protection which, of course, act cumulatively in practice, so that with the poorer magnetic qualities of the track rails, their failure to produce a simultaneous effect upon the audions, and the neutralizing or balancing action, the differentiation between the effects of the regular track elements and any magnetic bodies along the track is made so great as to permit satisfactory operation of the system under most unfavorable conditions of battery voltages, variations of air gap, and temperature changes.

In Fig. 3 has been illustrated a modified form of the invention wherein the audion has been omitted, and a modified form of relay R¹ has been substituted for the control relay R. This relay R¹ is provided with two independent windings 45 and 46, which correspond to the grids of the audions in the embodiment illustrated in Fig. 2. In the present embodiment of the invention the car elements L and M are disposed in the same manner as in the embodiment heretofore described. The secondary coil 20 on the car element L is connected through the winding 45 of the control relay R and in series with the battery B. This coil 20 is so wound and connected that the first wave of a unicyclic influence received by the car element L will generate a voltage in this coil opposing the voltage of the battery B. Likewise, the secondary coil 21 of the car element M has in series therewith another coil 46 of the relay R¹, and this partial circuit is connected to battery B in a similar manner. The circuit through the primary coils 18 and 19 and through the train control device K is the same as the one pre-

viously described, and is energized by the batteries B and C.

In this embodiment of the invention, shown in Fig. 3, the relay R¹ is so designed that when the circuit through either of its windings 45 or 46 is completed, the front contact 43¹ of the relay R¹ will be closed maintaining the circuit of the train control device K completed, and when the circuit through the other winding is completed the total ampere turns of the relay R¹ will be again as much more above the drop-away, thereby preventing the train control device K from applying the brakes or controlling the train in any other manner if only one of the car elements is affected at a time. The operation of this modified form of the invention is analogous to the embodiment illustrated in Fig. 2; and detail description of the operation is believed unnecessary.

Some of the characteristic features of this invention, in addition to the protection against rail interference to which attention has been more particularly directed, it will be observed consist in the fact that the various parts and circuits are constructed in accordance with the closed circuit principle of failure on the side of safety, that the trackway devices require no energy to change the controlling condition, and that the system provides for the transmission of a control influence from the trackway to moving vehicles inductively through an intervening air gap and without physical contact in a thoroughly dependable manner. In explaining this invention, it has been shown and described in its simplest form and without the various adjuncts that could be employed in practice to advantage; and I desire to have it understood that the particular structure shown and described does not cover or exhaust the many adaptations and modifications of the means for practicing this invention, nor include the various additions and applications of the invention to a complete system of train control.

What I claim is:—

1. Car-carried apparatus for automatic train control systems comprising, a pair of electro-responsive devices, a third electro-responsive device, each of said pair of devices normally supplying substantially the same amount of current to the third electro-responsive device, the current supplied by each of said pair of devices being sufficient to maintain said third electro-responsive device in its normal energized condition, and separate means for influencing each electro-responsive device of said pair.

2. Car-carried apparatus for automatic train control systems comprising, a car-carried core of magnetic material, a primary coil and two secondary windings on said core, a separate electro-responsive device

governed by each of said secondary windings, a normally energized control relay maintained, energized by both of said electro-responsive devices, each of said devices supplying enough energy to said control relay to maintain it in its energized position, and separate means for influencing each of said electro-responsive devices.

3. Car-carried apparatus for train control systems comprising, a plurality of car elements magnetically connected by a yoke to form a core having four projecting legs, primary windings on diametrically opposite legs, and secondary windings for receiving influences on the other legs, an electro-responsive device adapted to be actuated when an influence is received from each of said secondary windings simultaneously.

4. A car-carried element for receiving inductive control influences from the trackway for automatically controlling a train comprising, a back yoke having four downwardly projecting legs, normally energized primary coils on two of the legs, and secondary coils on the other legs.

5. Car-carried apparatus for train control systems comprising, a magnetic body having two diametrically opposite extending poles provided with magnetizing windings, and two diametrically opposite extending poles disposed in a different vertical plane provided with secondary windings, and a train control device adapted to be actuated by currents simultaneously induced in both of said secondary windings.

6. Car-carried apparatus for automatic train control systems comprising, a back yoke having four downwardly projecting legs arranged to form a quadrilateral figure, primary coils on a diagonally opposite pair of said legs, and secondary coils on the other two legs.

7. Apparatus as specified in the preceding claim, wherein the primary coils are wound and connected to a source of energy in a manner to form magnetic poles of opposite polarity.

8. Car-carried apparatus for automatic train control systems comprising, a back yoke of magnetic material having four downwardly projecting legs forming a quadrilateral figure, oppositely wound primary coils on two diagonally opposite legs, and oppositely wound secondary coils on the other two legs, and a normally energized train control device governed by said secondary coils and deenergized only when simultaneous influences of a predetermined character are received by said secondary coils.

9. In an automatic train control system, the combination of a car element comprising a magnetic body of four-cornered configuration and having a downwardly projecting leg at each corner, primary coils on two diagonally opposite legs energized to pro-

duce magnetic poles of opposite polarity, secondary legs on the other two legs each connected to control apparatus and adapted to transmit the proper control influence if 5 magnetically influenced from one but not the other of said primary coils, a normally energized train control device adapted to be deenergized only when simultaneous control influences of the proper kind are transmitted 10 by both of said secondary coils, and traffic controlled trackway means adapted to magnetically influence one of said secondary coils by one of said primary coils and the other secondary coil by the other primary coil simultaneously as the car element passes 15 over said trackway means.

In testimony whereof I hereto affix my signature.

NED C. L. BROWN.
